RAIL ANCHOR MEANS

Franklin Chapman, Mexico City, Mexico, assignor, by
mesne assignments, to Julio Serrano Segovia
Filed July 13, 1965, Ser. No. 471,619
13 Claims. (Cl. 238—315)

ABSTRACT OF THE DISCLOSURE

This application discloses a rail anchor which has one hook end to be hooked over one flange of a base of a rail, and has another hook end to be hooked around a protruding end of a bar embedded in an adjacent concrete tie which supports such rail.

Another similar rail anchor may be rotated 180° about a vertical axis and may be hooked over the other flange of the rail and around another protruding end of said bar or another bar on the other side of said tie.

This invention relates to rail anchor means.

One of the features of this invention includes rail anchor means whereby a railroad rail is anchored to a railroad tie in a simple and efficient manner by the use of a straight, rigid tie bar which is embedded in the tie with protruding tie bar ends at the sides of the tie, and by the use of an additional bar at each of the sides of the tie, each additional bar being bent in a simple but very efficient manner to form an anchor to grasp the adjacent flange of the rail base and the adjacent protruding end of the tie bar.

Another feature of this invention includes a homogeneous rail anchor, one end of which may be hooked over one flange of the base of a railroad rail and the other end of which may be hooked around a rail tie bar means which has protrusions from a rail tie which supports the rail.

Another feature of this invention includes a railroad rail construction in which a railroad rail is supported on a rail tie which is transverse to such rail and has opposite tie sides transverse to the rail, with the tie having a rigid tie bar means embedded therein below and parallel to the rail with the bar means having protrusions from such tie sides, and in which first and second rail anchors of the character of the above preceding feature are respectively placed in mirror image relationship adjacent such tie sides with each respective anchor having one respective end hooked over one flange of the base of the rail and with the respective other end of the respective anchor hooked around one respective protrusion of the rail tie bar means.

Another feature of this invention includes a railroad rail construction according to the above preceding features in which such rail is supported by a series of adjacent similar rail ties, which rail ties also similarly support another parallel companion rail to produce a complete railroad track with efficiently anchored rails.

Other features of this invention are apparent from this description, the appended claimed subject matter and/or the accompanying drawings, in which

FIGURE 1 is a diagrammatic side view of a rail anchor according to this invention, about to be secured to a railroad rail.

FIGURE 2 is a view similar to FIGURE 1 and showing the rail anchor secured to the rail and to a protruding end of a tie bar, the main body of which bar is embedded in a rail tie which supports the rail.

FIGURE 3 is a view of the anchor taken from line 3—3 of FIGURE 2.

2

FIGURE 4 is a view of the anchor taken from line 4—4 of FIGURE 2.

FIGURE 5 is a view taken from line 5—5 of FIGURE 2, but rotated 90°.

FIGURE 6 is a top diagrammatic view of a rail construction in which the rail is supported on a series of ties to which the rail is secured by a series of anchors of this invention.

FIGURE 7 is a diagrammatic cross-section along the line 7—7 of FIGURE 6.

FIGURE 8 is a diagrammatic view somewhat similar to FIGURE 2, and showing specific sizes used in one specific embodiment of this invention.

FIGURE 9 is a view taken from line 9—9 of FIGURE 8.

Certain words may be used in this specification and in the claimed subject matter which indicate direction, relative position, and the like. Such words are used for the sake of clearness and brevity. However, it is to be understood that such words are used only in connection with the direction, relative position, and the like, which are shown in the drawings, and that in actual use, the parts so described may have different direction, relative position, and the like.

A railroad track construction, according to this invention, may include a rail 20 which is one of a pair of parallel rails which forms the track construction. The rail 20 is supported on a series of parallel rail ties 22 which are substantially parallel to each other and are transverse to the rail 20.

The rail 20 may have a base 24 with a first flange 26 and an opposite second flange 28. Each of the flanges 26 and 28 may have a flat flange bottom surface 30, a flange top surface 32 and an edge surface 34 which joins such bottom and top surfaces 30 and 32.

The flange bottom surfaces 30, 30 are part of a substantially flat entire bottom rail surface 42.

Each rail tie 22 may have a tie body 36 which has opposite side walls 38 and 40 transverse to such rail 20 with a tie top surface 43 below such flat flange bottom surfaces 30, as well as below the entire flat rail bottom surface 42.

The flange bottom surfaces 30, 30 may be part of the substantially flat entire bottom rail surface 42.

A first rail anchor or anchor means 44 is placed adjacent one side 40 of the tie 22. Such anchor 44 may be made from a substantially rectangular metal anchor bar which is bent or formed to have an upper hook 46 which may be hooked over the first flange 26 with an upper hook portion 48 over a respective flange top surface 32. The hook 46 may also have a lower hook portion 52 which may be below the flange bottom surface 30. The hook 46 also may have a hook joining portion 54 which joins the upper hook portion 48 and the lower hook portion 52.

The anchor or anchor bar 44 may have a downwardly extending anchor portion 56 joined at its upper end to such lower hook portion 52. The portion 56 may have an outward intermediate bend 58, and may also have an inward and slightly upward lower bend 60. This upward, lower bend 60 may terminate in an upward hook portion 62 which is hooked around the edge 64 of the protruding portion 66 of a rigid tie bar or tie bar means 68.

The rigid metal tie bar means 68 may be embedded in the tie body 36 of the tie 22. The tie 22 may be made of concrete and may extend completely across the track construction so that the other end (not shown) of the tie 22 may similarly support a parallel companion rail (not shown) which forms the railroad track construction of this invention. The concrete tie 22 may be reinforced by suitable metal reinforcing means (not shown), which preferably is spaced and electrically insulated from the rigid metal tie bar 68.

The rigid tie bar 68 may be cast in the concrete tie 22 at the time that the tie 22 is made. It may be below and parallel to the rail 20, as shown in dotted lines in FIGURE 6. The tie bar means 68 may have opposite protruding ends or protrusions 66 and 70 which extend outwardly beyond the respective sides 40 and 38 of the tie 22.

A second rail anchor or anchor means 72 may be placed adjacent the other side 38 of the tie 22. Such second rail anchor 72 may, if desired, be identical with said first rail anchor 44 except that it has been rotated 180° about a vertical axis so that, as shown in FIGURE 7, the second anchor 72 is a mirror image of first anchor 44.

Such second rail anchor 72 may have its upper hook 46' hooked over the second flange 28 of the rail 20 and may have its upward hook portion 62' hooked around the other edge of the other protruding portion or protrusion 70 of the tie bar means 68.

The first anchor 44, for example, may be attached to the rail flange 26 and the tie bar 68 by placing such anchor adjacent such flange 26 and bar 68, as shown in FIGURE 1. Then a rightward force 74 (FIGURE 1) in the order of 5000 pounds, for example, is applied to the downwardly extending portion 56, such as at the intermediate bend 58, as indicated by the arrow 74 so that the upper hook 46 and lower hook portion 62 are forced from their positions in FIGURE 1 to their respective positions as shown in FIGURE 2. The hook 46 is thus completely pushed over the flange 26 and the lower hook portion is hooked or forced around the tie bar 68.

Before, simultaneously, or thereafter, the second anchor 72 is placed adjacent the other rail flange, and the other protruding end 70 of the tie bar 68 and adjacent the other side 38 of the tie 22. A leftward force of 5000 pounds is applied similarly, but in mirror image relationship, to the force 74 previously described. This causes the second anchor 72 to be forced into hooked engagement with the second flange 28 of the rail and with the opposite edge of the outwardly protruding end 70 of the tie bar 68.

The two anchors 44 and 72, on opposite sides of the rail 20 and on opposite sides of the tie 22, cooperate with each other to lock the rail 20 against sidewise displacement and against sidewise tilting or torsional displacement by the sidewise forces of the passing train, whether the rail is on a straight part of the track or on a curved part of the track.

Also the adjacent ties 22 such as the upper tie 22 of FIGURE 6 and a similar tie below FIGURE 6, not 50 shown, and their cooperating and similar anchors also cooperate further to reinforce the stabilizing forces of the series of anchors and ties that make up the track construction of this invention.

Merely by way of example, FIGURES 8 and 9 indicate certain dimensions of the rail anchor means as applied to a typical railroad rail. FIGURE 8 corresponds substantially to the anchor means shown in FIGURE 2 and the description previously given in connection with FIGURE 2 applies to FIGURE 8. Therefore, the reference numerals which have been applied to FIGURE 2 also apply to corresponding parts of FIGURE 8. However, such reference numerals are not repeated in FIGURE 8. FIGURE 9 shows the upper end of the anchor shown in FIGURE 8.

The rectangular end of the tie bar of FIGURE 8 which corresponds to 68 of FIGURE 2, as well as the entire bar 68, may be 1 inch in horizontal dimension and $\frac{1}{2}$ inch in vertical dimension. Other dimensions are indicated in FIGURES 8 and 9 by letters of the alphabet and such dimensions are in inch ("") measurements and may be as follows: $A=4\frac{1}{2}$ ", $B=6\frac{1}{8}$ ", $C=1\frac{1}{16}$ ", $D=5\frac{5}{8}$ ", $E=3\frac{1}{16}$ ", $F=7\frac{7}{8}$ ", $G=2\frac{7}{16}$ ", $H=1\frac{1}{8}$ ", $J=1\frac{1}{2}$ ", $K=7\frac{7}{16}$ ", $L=1\frac{1}{4}$ ", $M=5\frac{5}{8}$ ", $N=5\frac{5}{8}$ ", $P=5\frac{1}{2}$ ", $Q=7\frac{7}{8}$ ", $R=1\frac{1}{4}$ ", $R^1=1\frac{1}{16}$ ", $S=11\frac{11}{16}$ ", $T=1\frac{1}{4}$ ". However, these dimen-

sions are given by way of example and may be varied as desired.

The rectangular bar which forms the tie bar 68 may protrude 2 inches beyond the sides 38 and 40 of the tie 22. The sides 38 and 40 of the tie 22 may be straight parallel vertical sides. The ties 22 may be substantially at right angles to the longitudinal axis of the rail 20.

The bars which form the tie bar 68 and form the anchors 44 and 72 may be made of any suitable steel and may be treated to have the required characteristics herein described. Such bars with the required treatments thereof may be made and formed by any of those skilled for this purpose in the steel industry.

The tie bar or tie bar means 68 is placed in proper position before the concrete for the tie 22 is poured. Therefore, such tie bar means is an integral part of the tie. The bar 68 serves an important function in reinforcing the concrete, as it runs directly under and parallel to the rail, where the maximum impact is, for example, 64,000 pounds, with a diesel engine load.

The anchor means of this invention provides important torsional forces. When a fast, heavy train rounds a curve, the anchor means exerts a lateral force against the rails to counteract the lateral force of the train. Torsion forces of this invention take over and tightly hold the rail by the action of the two anchors 44 and 72 at the tie bar 68 and the rail flanges 26 and 28. Also the two anchors provide large torsional forces to prevent longitudinal slippage of the rail when the heavy train is braked.

It is thus to be seen that a new, useful and unobvious rail anchor means has been provided by this invention.

While the form of the invention now preferred had been disclosed as required by statute, other forms may be used, all coming within the scope of the claimed subject matter which follows.

What is claimed is:

1. Rail anchor means comprising:
a rail having a base with a first flange and an opposite second flange, each flange having a flat flange bottom surface, a flange top surface, and an edge surface joining said bottom and top surfaces;
a rail tie with opposite side walls transverse to said rail and with a top surface below said flat flange bottom surfaces;
a rigid tie bar in said tie below and parallel to said rail, said tie bar having opposite protruding ends extending outwardly beyond said side walls, and having opposite tie bar edges;
a first rail anchor adjacent one side wall, said anchor including an anchor bar having an upper hook hooked over said first flange with an upper hook portion over a respective flange top surface, with a lower hook portion below said flange bottom surface, and with a hook joining portion joining said upper hook portion and said lower hook portion, having an outward intermediate bend, and having an inward and slightly upward lower bend, said upward lower bend terminating in an upward hook portion hooked around one edge of the adjacent protruding end of said tie bar;
a second rail anchor adjacent the other side of said tie, said second rail anchor being a mirror image of said first rail anchor and having its upper hook hooked over said second flange and having its upward hook portion hooked around the other edge of the other protruding portion of said tie bar.
2. A rail anchor means according to claim 1 in which said flange bottom surfaces are part of a substantially flat entire bottom rail surface and in which said rail tie has a substantially flat top surface under said flat entire bottom rail surface.
3. A rail anchor means according to claim 2 in which said tie is a concrete tie and said tie bar is embedded in said concrete tie.
4. Rail anchor means comprising:

- a rail having a base with a first flange and an opposite second flange;
- a rail tie having a first side wall and an opposite second side wall, said side walls being transverse to said rail, said tie having a top surface below said base;
- a rigid tie bar means embedded in said tie below and parallel to said rail, said tie bar means having a first protrusion and an opposite second protrusion, said protrusions extending outwardly beyond said side walls;
- a first rail anchor adjacent said first side wall, said first anchor including a first anchor bar having a first upper hook hooked over said first flange, having a first downwardly extending anchor portion joined to said hook, and having a first inward lower bend terminating in a first upward hook portion hooked around said first protrusion;
- and a second rail anchor adjacent said second side wall, said second rail anchor including a second anchor bar having a second upper hook hooked over said second flange, having a second downwardly extending anchor portion joined to said second hook, and having a second inward lower bend terminating in a second upward hook portion hooked around said second protrusion.
5. Rail anchor means comprising:
- a rail having a base with a first flange and an opposite second flange;
- a rail tie having a first side wall and an opposite second side wall, said side walls being transverse to said rail, said tie having a top surface below said base;
- rigid tie bar means embedded in said tie below and parallel to said rail, said tie bar means having a first protrusion and an opposite second protrusion, said protrusions extending outwardly beyond said side walls;
- a first rail anchor adjacent said first side wall, said first anchor having a first upper hook means hooked to said first flange, having a first downwardly extending resilient portion joined to said first hook means and terminating in a first lower hook means hooked to said first protrusion;
- and a second rail anchor adjacent said second side wall, said second anchor having a second upper hook means hooked to said second flange, having a second downwardly extending resilient portion joined to said second hook means and terminating in a second lower hook means hooked to said second protrusion.
6. Rail anchor means having an upper hook means to be hooked to a flange of a base of a rail adjacent a side wall of a rail tie, said anchor having a downwardly extending resilient portion joined to said hook means and terminating in a lower hook means entirely below said rail

- to be hooked to a protrusion of a tie bar means below said rail which is embedded in a tie which supports said rail.
7. Rail anchor means comprising a rail anchor made of a homogeneous metal anchor bar having an upper hook to be hooked over a flange of a base of a rail adjacent a side wall of a rail tie, said anchor bar having a downwardly extending anchor portion joined to said hook and having an inward lower bend terminating in an upward hook portion entirely below said rail to be hooked around a protrusion of a tie bar means below said rail which is embedded in a tie which supports said rail.
8. Rail anchor means having upper attaching means to be attached to a flange means of a base of a rail adjacent the side wall of a rail tie means, said anchor means having a downwardly extending anchor portion means joined to said upper attaching means and having a lower attaching means entirely below said rail to be attached to a protrusion means of a tie bar means below said rail, which is embedded in a tie means which supports said rail.
9. Rail anchor means according to claim 8 which is shaped so that it can be rotated 180° about a vertical axis and be attached to the opposite flange means of said base of said rail adjacent the opposite side wall of said rail tie means and to the opposite protrusion means of said tie bar means which extends from said opposite side wall of said rail tie means.
10. Rail anchor means according to claim 9 which is homogeneous throughout.
11. Rail anchor means having upper attaching means to be attached to a flange means of a base of a rail adjacent the side wall of a rail tie means said anchor means having a downwardly extending anchor portion means joined to said upper attaching means and having a lower attaching means entirely below said rail to be attached to a tie attachment means located below said rail at said side wall of said rail tie means.
12. Rail anchor means according to claim 11 which is so shaped that it can be rotated 180° about a vertical axis to provide a second anchor means to be attached to the opposite flange of said base of said rail adjacent the opposite side wall of said tie means and to an opposite tie attachment means located below said rail at said opposite side wall of said tie means.
13. Rail anchor means according to claim 12 in which said second anchor means is a mirror image of said first named anchor means.
